US00D970203S

(12) **United States Design Patent** (10) **Patent No.:** **US D970,203 S**
(45) **Date of Patent:** **** Nov. 22, 2022**

(54) **WEARABLE SHOE TREE**

(71) Applicant: **Wearable Shoe Tree, LLC**, Frisco, TX (US)

(72) Inventor: **Paul Siragusa**, Frisco, TX (US)

(**) Term: **15 Years**

(21) Appl. No.: **29/839,382**

(22) Filed: **May 20, 2022**

Related U.S. Application Data

(62) Division of application No. 12/670,923, filed as application No. PCT/US2008/009165 on Jul. 30, 2008.

(57) **CLAIM**

The ornamental design for a wearable shoe tree, as shown and described.

DESCRIPTION

FIG. 1 is a perspective view of a wearable shoe tree, showing my new design;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.

The dash-dash broken lines in the drawings depict portions of the lock box that form no part of the claimed design.
